ADJUSTABLE MILL UNIT

Edwin G. Eppenbach, Manhasset, and Henry Imshaug, Flushing, N. Y.; said Imshaug assignor to said Eppenbach

Application March 1, 1944, Serial No. 524,823

4 Claims. (Cl. 241—259)

1

This invention relates generally to mills of devices for grinding, milling and mixing of material, such as is used in the production of colloidal compounds, and especially to the adjustment features of the mill units employed in such devices.

The present invention is a continuation in part of our co-pending application Serial No. 437,979, filed July 7, 1942, for Vertical mill, and its major object is to provide simple, effective and accurately operable means whereby the elements of mill units may be precisely adjusted relative to one another, and wherein are provided readily visible means for calibrating such adjustment and other means for locking the adjusting means in the desired position.

While the adjustment of mill elements relative to one another is nothing new in the art, this operation becomes exceedingly important in devices where material of fine texture is to be prepared, and especially when material which is to be processed is intended to be milled to a certain fineness in order to bring it to a state of colloidal suspension within a liquid carrier.

In such devices it becomes imperative that the adjustment of the mill elements to be very accurate, and that the amount of such adjustment becomes readily perceptible to the operator from without the device so as to facilitate accurate readjustments as may be required due to either the desire to increase the fineness of the product, or to compensate for the wear of the mill elements in the course of continuous operation of the device.

The foregoing important objects and advantages will become more fully understood from the following description, in connection with the accompanying drawings, wherein:

Fig. 1 illustrates an elevation of a device employing adjustable mill elements, shown partially in section;

Fig. 2 illustrates an enlarged partial detail view of the grinding and milling mechanism;

Fig. 3 is a similar illustration of a modified form of the grinding and milling arrangement;

Fig. 4 is an enlarged detail view in vertical cross section of the mill unit and its adjusting means; and

Fig. 5 is a plan view of the adjusting nut thereof.

Referring now specifically to the drawings, numeral 10 denotes the base of the device, which is preferably placed upon the floor, but which may be swung to any desired position and secured in that position by bolts or other means

not shown in the drawings. Within base 10 there is suspended a motive source 11, such as an electric motor, with a vertical shaft 12 extending upwards. The motor is suspended from the enclosed bottom structure 13 of a frame 14, which latter rests upon base 10. The center of frame bottom 13 is apertured at 15, which aperture is covered by a drip guard 16. Structure 13 and drip guard 16 effectively prevent liquid or moisture from entering the base and damaging the motor.

Secured to and supported by frame 14 is a combination journaling and adjusting member 17, consisting of a hub structure 18, with which 15 is associated a threaded adjustable cup 19, accommodating a shaft bearing 20. Cup 19 may be set in its adjusted position in respect to hub 18 by set screws 21. Within hub 18 is lodged and guided a sleeve 22, which is threaded externally 20 at 23 and is engaged by an internally threaded and calibrated index ring 24, by means of which ring sleeve 22 may be adjusted in upward or downward directions. Sleeve 22 may be held in its adjusted position by means of set screw 25 engaging ring 24.

Within sleeve 22 and journaled in bearings 20 is rotor shaft 26. The latter is joined with shaft 12 of motor 11 by means of coupling 27, located within frame 14. Secured to shaft 26 is rotor 28, forming a part of the grinder or mill unit 30 of the device. Rotor 28 is exchangeable. The stator of the mill is indicated at 29 and also comprises an exchangeable member or insert, which is supported by the broadened upper or flanged end 30 of sleeve 22, and which broadened end forms the bottom of the mill casing, which houses the grinder unit. It will be seen that the casing is provided with a water jacket 31, whereby the casing, and therefore the grinder unit, may be readily cooled or held at any desired temperature required for the matter to be treated within the device.

Above jacket 31 is a jacketed top member 32, held together with flange 30 of sleeve 22 by means of spacer bolts 33. Supported by upper jacket structure 32 is a hopper 34, provided with a cover 35, which may be completely closed if so desired. By means of the jacket in member 32 the contents of the hopper may be kept at any desired temperature. The top of the hopper is provided with an inlet 36 into which is removably placed the end of the goose neck 37 forming the upper portion of conduit 38, joined at its lower end with outlet pipe 39. The latter is connected at 40 with the grinder unit, and its discharge is controlled

by valve 41. This valve may be so placed that it either provides a direct discharge from the grinder unit through its hollow structure 42, or that it closes outlet pipe 39 to provide circulation of the matter being milled through pipe 38 to the top of hopper 34 and back into the grinder.

Referring now to Figs. 2 and 3, these detail figures illustrate two forms of the grinding unit. In Fig. 2 shaft 26 is provided with a reduced portion 43, and a threaded end 44, with which two portions one-piece rotor 28 is associated. Stator 29 comprises also a one-piece structure and is supported by the upper flanged end 30 of adjustable sleeve 22.

Fig. 3 illustrates a somewhat modified form of the mill elements. In that figure shaft 26 is again reduced at 43, but is provided with a much longer threaded end 44', by means of which a multiple-piece rotor is secured to the shaft. In this construction the rotor comprises a supporting member 45, a cover member 46 and an exchangeable insert 47, which may be in the form of an abrasive ring. The latter is clamped between members 45 and 46. The stator of this modified form is also provided with an exchangeable abrasive element 48, lodged within the inverted dish-structure 49.

Attention is now invited to Figs. 4 and 5, and especially to the arrangement including the mill unit and its adjusting means. It will be observed that frame 14, within which the shaft coupling 27 operates, serves as support for the entire upper structure of the mill device, over which is mounted hopper 34. Frame 14 also serves for attaching that structure, such as by bolts 50.

The combination journaling and adjusting means 17 include a hollow body 51, the base 18 of which is secured by the aforesaid bolt 50 to frame 14. Extending from body 51 are upper 40 journaling hub 52 and lower journaling hub 53, which latter is externally threaded. These journaling hubs serve as supports and journals for guide sleeve 22. It will be noted that upper hub 52 is provided with an opening 54 in registry with opening 55, provided in guide sleeve 22, in order to facilitate the lubrication of shaft 26 within the guide sleeve.

The lower threaded end of hub 53 is engaged by the internally threaded portion of adjustable bearing cup 19, in which is lodged thrust bearing 20 for shaft 26. In the lower end of cup 19 there is provided at 56 a packing ring adapted to prevent the escape of lubricant passed through passage 55 into guide sleeve 22.

The thrust bearing 20 supports shaft 26, while in guide sleeve 22 bearings 57 and 58 are provided to correctly journal shaft 26 and its rotor in respect to the stator. Stator 29 is held in its correct position by means of an inlay 59, secured by means of bolt 60 passing through flange 30 of guide sleeve 22. This insert not only holds stator 29 in position, but also provides a seal between the rotor and the stator, so that the material milled by the unit is discharged into an annular space indicated at 61, from which it passes into conduit 39.

The adjusting means for guide sleeve 22, whereby the stator may be positioned at the desired distance from the rotor, are located within the hollow portion of enlarged body 51 secured to frame 14. The internal structure of body 51 provides two oppositely disposed parallelly machined surfaces between which operates the hub of ring or nut 24. The outer faces of

the ring hub are also machined, and the height of the hub substantially corresponds to the distance between the machined surfaces in body 51, which surfaces form end abutments for the ring hub. Thus the ring is operatively held between these end abutments and can not move axially, whereby its movement is restricted to a purely rotary motion.

The ring hub is provided with an internal thread 62 which engages external thread 23 of sleeve 22. Extending from the ring hub is a web which supports an annular enlargement wherein a plurality of radial recesses 63 are provided to facilitate turning and adjustment of the ring in respect to casing 51, which latter has a spare-out 64 in its otherwise closed, hollow body to provide access to recesses 63 and to allow rotation of the ring through a short arc.

The upper portion of the annular ring enlargement is beveled, and upon that beveled portion there is provided a calibrated strip 65. Secured to the upper ledge of spare-out 64 is an indicator 66 pointed toward the calibration on strip 65. At the top portion of the ring annulus 25 there is provided a plurality of recesses 67, seen clearly in Fig. 5, and serving for the reception of the reduced lower end of set or lock screw 25, operatively mounted in the upper ledge or cover portion of journaling body 51.

By means of radial recesses 63 of the nut, the latter may be turned with relative ease, whereby an exact adjustment of the stator in respect to the rotor is facilitated. Indicator 66 denotes such adjustment on the scale or calibration 65, and lock screw 25 screwed down into one of the recesses 67 of the nut holds the latter against movement.

When it becomes evident from the product leaving the mill, or for any other reason, that a re-adjustment of the mill unit is required, such new adjustment may be easily and accurately made by simply elevating lock screws 25 above the nut and turning the latter to a desired mark of the calibration, whereupon screw 25 is again lowered into one of the recesses 67. The amount of adjustment may be usually determined for different types of work before the device is put into use, whereby the necessity of employing skilled manipulators is effectively overcome. It is merely necessary to give directions to what setting nut 24 is to be advanced after stated operating periods of the mill.

While the above described arrangement is primarily designed for adjusting the stationary element of the mill unit in respect to the rotor, the latter is rendered adjustable also. Bearing cup 19 in thread engagement with lower journaling hub 53 accommodates thrust bearing 20 of rotor shaft 26. By unscrewing or tightening cup 19 in respect to hub 53, the shaft may be lowered or raised. One or more set screws 21 provided in cup 19 will keep the latter in the desired adjusted position.

Although we have shown and described certain specific constructions of our adjusting means for the mill elements, it is obvious that changes and improvements may be incorporated therein, without departing from the broad scope of our invention, as defined in the annexed claims.

We claim:

1. In a colloidal mill device, a frame, a motive source suspended from the frame, a mill structure supported by and removably secured to the frame, said mill structure including combination journaling and adjusting means, said journaling

means forming a hollow body, serving for attachment of the mill structure to the frame, with upper and lower guide hubs extending from the hollow body, a bearing cup adjustably associated with the lower guide hub and accommodating a thrust bearing, a mill shaft operative by said motive source journaled in said bearing, a guide sleeve for the shaft slidably mounted in said guide hubs; said adjusting means being operative within the hollow body of said journaling means and engaging said sleeve for adjusting the latter, a mill rotor associated with said mill shaft, said rotor being rendered adjustable in respect to said guide sleeve by way of said mill shaft through the adjustable bearing cup, a mill stator supported by said guide sleeve and being adjustable in respect to the mill rotor by way of the guide sleeve through said adjusting means in operative engagement with said guide sleeve, and means for arresting the movement of said adjusting means in the adjusted position.

2. In a colloidal mill device, as set forth in claim 1, said calibrated adjusting means comprising an internally threaded member operative between end abutments, thus restricting its operation to a rotary movement only, its internal thread engaging the externally threaded portion of said stator support, means provided with said member for facilitating its rotary operation, and a calibration arranged peripherally on said member for setting it, said arresting means comprising recesses in said member engageable by a lock screw to hold the member in its set position.

3. In a mechanism for adjusting elements of mill units in colloidal mill devices and the like, an adjustable guide sleeve for journaling the shaft of the movable element of the mill unit, said guide sleeve serving as support of the stationary element of the mill unit, and means restricted to a purely rotary movement by fixed abutments, and being in operative engagement with said sleeve for adjusting the latter, and thus the stationary element, relative to the movable element, and means for setting said adjusting means, and other means for arresting said adjusting means in the set position.

4. In a colloidal mill device having an adjustable mill unit, a centrally apertured fixed support for the mill unit including an annular hollow, substantially closed body enlargement, a sleeve adjustably mounted in the apertured portion of the support and provided with a flange to which the mill stator is attached, a rotor shaft operative in said sleeve and being adjustable both in respect to said sleeve and to said support, means operative within said body enlargement for adjusting the sleeve, and thus the stator, in respect to the support and the rotor, means in said enlargement for restricting the movement of said adjusting means to a rotary operation only, and other means operative from without said enlargement for preventing the movement of said adjusting means.

EDWIN G. EPPENBACH.
HENRY IMSHAUG.
